UNITED STATES PATENT OFFICE.

GEORGE A. MINZEY, OF BROCKTON, MASSACHUSETTS, ASSIGNOR TO ELLERY C. WRIGHT, OF BROCKTON, MASSACHUSETTS.

LAST.

1,100,663.

Specification of Letters Patent.

Patented June 16, 1914.

Application filed September 25, 1913. Serial No. 791,771.

To all whom it may concern:

Be it known that I, GEORGE A. MINZEY, a citizen of the United States, and resident of Brockton, county of Plymouth, State of Massachusetts, have invented an Improvement in Lasts, of which the following description, in connection with the accompanying drawings, is a specification, like letters on the drawings representing like parts.

10 This invention relates to two-part lasts, and its object is to strengthen the construction of the heel portion of such lasts, to provide a rigid member connecting the heel part and forepart which will also act as a brace 15 or support for the last in use, and to improve and perfect this type of last.

In the manufacture of lasts having two parts it has heretofore been very difficult to provide a construction which was sufficiently 20 strong to withstand the blows and pressures to which a last is subjected in use and consequently two-part lasts are defective in their capacity to endure the strains to which 25 they are subjected in ordinary shoe factory use.

My present invention is a two-part last, with a rigid connecting member which will enable such a last to be made without cutting any slots or making grooves or the like 30 in the wood of either part, particularly in the abutting faces or surfaces of the forepart and heel part where the same contact.

By means of my invention I am enabled to leave the wood in the heel part substantially entire and simply bore a relatively small cavity in the center of the fore-part, which does not materially weaken the wood of the fore-part, and unite both heel part and fore-part by means of a rodlike connecting member which will also serve to cooperate with the abutting faces of the two parts in affording increased rigidity and strength to the last when it is subjected to the sole leveling and heeling pressures. I 45 also provide means to distribute the strains in the heel part throughout the more solid and thicker portions of the wood. In my improved last I am also enabled to provide a relatively high pivot point in the fore-part 50 on which the two parts may swing to secure a more rapid shortening of the last when the parts are flexed for insertion in or removal from a shoe, this having the further advantage of enabling the pivot to be in the

thicker and stronger portions of the wood of 55 the forepart.

Other features of the invention, details of construction and novel combinations of parts will be hereinafter more fully pointed out and claimed.

Referring to the drawings, illustrating a preferred embodiment of the invention, Figure 1 is a side view, partly in section, of my improved last; and Fig. 2 is a view partly in section on the line 2-2 of Fig. 1.

In the drawings 1 is the forepart and 2 the heel part of a two part last. Preferably I make the line of cut or division between these two parts with straight meeting faces, as shown at 3 and 4, together with the usual 70 V-shaped faces 5 and 6 to permit the parts to be flexed, the last named lines of cut being just sufficient to permit the amount of flexing desired, thus reducing to a minimum, the cutting away of the wood of the last. 75 Preferably these lines of cut 3 and 4 are made substantially at right angles to each other, as shown, in the drawing, thereby constituting a recess in the heel portion and the coöperating projection in the forepart, 80 this form enabling me to advantageously position the pivot member together with my novel form of means for uniting the two parts. I utilize a rodlike member as this means and bore a suitable socket 7 therefor 85

in the heel part, and a corresponding socket 8 in the fore-part, the latter being sufficiently enlarged to permit the rodlike connecting member 9 to oscillate when the two parts are flexed to shorten the last. This member 90 9 is preferably in the form of an elbow, having a portion adapted to fit snugly in the sockets 7, which is formed approximately in the central part of the heel portion where the wood is firm and solid, while the other 95 portion of the member 9 extends in the socket 8 and is pivotally mounted on a pin 10, which passes through the wood of the forepart 1, being in the solid wood of the last excepting only where it passes through 100 the bore 8 and into said member 9. This pin 10 can be fitted in a relatively high position, from the extreme bottom of the last, thus affording firm bearings in the wood of the forepart. It will be noted also that the 105 pivot pin 10 is substantially in line with the face 5, so that said pin is in very firm wood of the forepart 1. Passing through the heel

part and through a suitable socket therefor in the other end of the member 9 is a bolt 11, preferably constituting a compression member with heads on either end, similar to the 5 compression bolt illustrated in Patents 605, 768 and 642,945, which thus binds the elbow or connecting member 9 rigidly in the heel part and at the same time holds the wood of the heel part under compression adjacent 10 the socket 7. As a still further strengthening means for the elbow 9 and the heel part 2, I provide a similar tension bolt 12 vertically of the heel and passing through the member 9, as clearly shown in Figs. 1 and 15 2. This second bolt is preferably headed underneath the heel clenching plate 13, and is protected thereby. I also strengthen the heel portion with the usual tension bolts 14 and 15 underneath and at the rear of the 20 thimble 16, respectively, as is customary. To keep the two parts in extended position, a spring 17 fitting in bored sockets 18 and 19 is also arranged as shown.

In use, it will be seen that my improved 25 construction provides a last having the heel part so strengthened that the heel thereof will receive and consequently resist the strains to which the last is subjected, in the firm and solid parts of the heel. The member 9 being fitted substantially midway between the heel plate 13 and the top or cone of the last 20, is in the best position to be firmly and solidly held, and by its bearing upon the vertical tension bolt 12 and the 35 transverse tension bolt 11, it is most firmly secured. With the last in extended position also, the meeting edges 3 and 4 of the heel and foreparts present an unbroken surface to transmit strains and pressure, 40 free of any slots or other weakening cuts, and furthermore the member 9 is so arranged as to afford an additional bearing surface at 21 on the wood of the forepart so that the several surfaces 3, 4, and 21 provide 45 a firm locking means to resist leveling or collapsing pressures or the like when applied to the bottom of the last. I consider this feature of the member 9 coöperating

with the lines of cut 3 and 4 as of importance in affording additional strain resisting means. The pintle pin 10 and the connecting member 9 may be of any suitable size to afford the desired strength for a particular last and the special uses to which it may be put. The relatively high pivot 55 point 10 in the forepart together with the elbow form of the member 9 affords a very quick shortening of the last, when the two parts are flexed, and enables it to be fitted in or removed from a shoe with exceptional 60 ease, speed and facility.

Having described my invention, what I claim as new and desire to secure by Letters Patent is:

1. A two-part last, comprising a forepart and a heel part, and a rodlike member having one end portion rigidly secured in said heel part and its other end portion extending substantially at a right angle to said rigidly secured portion and pivotally connected to said forepart.

2. A two-part last, comprising a forepart with a vertical socket therein and a heel part with a horizontal socket therein, a rodlike member having two arms, substantially 75 right angled to each other, one arm being firmly seated in the socket in said heel part and its other arm pivotally fitting in the vertical socket in the forepart, and of less diameter than said socket, and pivotal 80 means securing said arm to the forepart.

3. A two-part last, comprising a forepart with a vertical socket therein and a heel part with a horizontal socket therein, and a rodlike member of elbow form firmly secured 85 in the socket of the heel part by horizontal and vertical tension bolts and pivotally secured in the socket of the forepart.

In testimony whereof, I have signed my name to this specification, in the presence of 90 two subscribing witnesses.

GEORGE A. MINZEY.
